UNITED STATES PATENT OFFICE.

FRANK H. BROWN AND JOHN E. HANRAHAN, OF BALTIMORE, AND GEORGE A. BOYDEN, OF MOUNT WASHINGTON, MARYLAND, ASSIGNORS TO NATIONAL COMPOSITYPE COMPANY, A CORPORATION OF DELAWARE.

TYPE MOLD AND MATRIX.

No. 845,686.

Specification of Letters Patent.

Patented Feb. 26, 1907.

Application filed May 19, 1905. Serial No. 261,163.

To all whom it may concern:

Be it known that we, FRANK H. BROWN and JOHN E. HANRAHAN, of the city of Baltimore and State of Maryland, and GEORGE A. BOYDEN, of Mount Washington, in the county of Baltimore, State of Maryland, citizens of the United States, have invented certain new and useful Improvements in Type Molds and Matrices, of which the following is a specification.

This invention relates to type-molds, and has among its objects to provide a mold by which type of a wide range of sizes and styles may be cast and by which the changes from one size type to another may be made quickly and the centering of the type character on the matrix with respect to the mold-cavity be made accurately without measurement and by unskilled labor.

The invention is illustrated in the accompanying drawings, in which—

Figure 1 shows a perspective view of the mold parts. Figs. 2, 3, and 4 show sectional views of insert-molds and portions of ejectors of various sizes. Figs. 5, 6, 7, 8, 9, and 10 show matrix-plates all of a uniform or equal size irrespective of the different-size characters they contain. Figs. 11 and 12 show space or quad matrix plates. Figs. 13, 14, 15, 16, 17, and 18 show type of varying sizes cast from matrices the plates of which are of uniform size, all cast from the same stationary mold part. Figs. 19 and 20 show spaces and quads of different sizes. Fig. 21 shows a longitudinal section through the insert-mold part with the matrix-holder and matrix held in place by the adjusting or centering screw, and Fig. 22 shows a perspective view of the matrix-holder with the centering recess in the rear side thereof.

Heretofore it has been the practice in making type, spaces, and quads to have separate mold mechanism for each bodywise size of type and to use matrices formed in plates varying widely in dimensions to accord with the size of the type to be made. This old method requires a change of all the mold parts and numerous adjustment of same each time a change is made from one size or kind of type to another and also requires numerous adjustments of the matrices with respect to the mold to get the type character on the matrix properly situated or centered,

the whole requiring skilled labor of exceptional ability. The difficulties inherent in this method have resulted in confining the manufacture of type to foundries provided with special equipment and skilled labor, and the type thus produced has been sold from the foundries and distributed to printers throughout the country.

The present invention contributes in an important manner to the overcoming of many of the difficulties herein mentioned and enables the method or practice alluded to be dispensed with.

The mold in this instance consists of four parts—a stationary mold part 1, which in practice is permanently attached to the casting mechanism and is used to cast all kinds and sizes of type within the size range of the machine; an insert-mold part 2, an ejector 3, and a matrix.

The plate or body part of the matrices will be of a uniform size irrespective of the size or kind of type character; but the insert-mold parts and the ejectors will vary in size as to their bodywise capacity, and the different sizes will be interchangeable with respect to the stationary mold part. The arrangement, construction, and operation of all these parts is such that their adjustment for type of different sizes will not require special skill.

The stationary mold part consists of a base-block 4, which forms the bottom wall of the type-cavity and is provided with a nipple-plate 5, through a hole in which (not shown) the metal is supplied to the mold-cavity in casting. An abutment 6 is attached rigidly to the base-block 4, and against this abutment a shoulder on the ejector 3 strikes when it is in the casting position. A series of thin plates 7 of different thicknesses, which we term "liners," are employed. Any selected number of these liners may be placed against the abutment 6 to govern the position of the ejector, and thereby regulate the setwise size of the type-cavity to correspond with the type characters.

On top of the base-block is the ejector 3, which forms one side wall of the type-cavity. This ejector has a reciprocating movement on the base-block 4, by which the type is ejected from the mold parts after being cast. In one side of the ejector is a recess 8, which permits the reciprocation of the ejector past the

abutment 6. A shoulder at one end of the said recess strikes against the abutment 6 (or against the liners 7 when the latter are inserted) when the ejector is in the casting position, as before stated.

The insert-mold part 2 consists of a right-angle piece which forms two of the walls of the mold-cavity—that is, the top and one side—when placed in position with respect to the stationary mold and ejector. The insert-mold part is provided with a recess 11 and a matrix-holder which receives and properly locates any one of the matrices irrespective of the size or kind of type to be cast, and this matrix-holder consists of a backing-plate 9, provided with projecting flanges 10, so arranged that each matrix of the font or any matrix of any font can be readily placed in said holder between said flanges in proper position for casting purposes without measuring or requiring skill. This matrix-holder containing the desired matrix, is then placed in a recess 11 in the insert-mold part especially designed to receive it, and by means of a centering-screw 12, having a cone-shaped end 13, which enters a similarly-shaped recess 14 in the matrix-holder, said holder containing the matrix may be accurately centered by merely turning the screw, which also holds and keeps the holder and matrix in proper position in the insert-mold part.

All matrix-plates to be used with the mold mechanism are to be of a uniform size irrespective of the size or kind of type characters, spaces, quads, or ornament to be cast from them, and the type character in each and all of the matrix-plates has the same predetermined position with respect to one vertical edge and the bottom edge of the plate and is so located that every matrix of a font or of a series of fonts is interchangeable with the mold mechanism. In changing from one set-wise size type character to another all that is required to center the character on the matrix with respect to the mold-cavity is to place the matrix in the matrix-holder 9 and secure the holder and matrix in the insert-mold part 2 by turning the screw 12. The matrix-holder will thereby be shifted to accurately center the matrix character with respect to the mold-cavity, and the whole is ready for casting the type selected without having required skilled labor.

It will also be seen that no matter what the size of the character on the matrix-plate may be the turning of the screw will cause the character to take its correct position, and the adjustment is the same in every case.

It will also be seen that as the matrix-plates are all of a uniform size and the characters thereon have the same position with respect to two edges of the matrix-plate when a matrix is placed in the holder the character irrespective of its size will have the same definite position with respect to the re-

cess in the back of the holder, and therefore the centering of the matrix can be readily accomplished by the adjusting-screw entering said recess.

Having thus described our invention, what we claim as new, and desire to secure by Letters Patent, is—

1. In a machine for casting type, the combination of a type-mold having a movable ejector forming one side of the mold-cavity; a matrix-plate having a casting-surface whose area is of size sufficient to receive any type character from the smallest to the largest dimensions for which the machine has capacity—said character, irrespective of its size, being situated on the said plate at a predetermined measurement from one vertical edge and the bottom edge of said plate; and insertible and removable liners which by limiting the movement of the ejector governs the setwise size of the mold-cavity.

2. In a machine for casting type, the combination of a type-mold comprising a stationary part and an insertible part; a matrix-plate carried by the said insertible part and having a casting-surface whose area is of size sufficient to receive any type character from the smallest to the largest dimensions for which the machine has capacity—said character, irrespective of its size, being situated on the said plate at a predetermined measurement from one vertical edge and the bottom edge of said plate; and means also on the insertible part of the mold to shift the matrix-plate so as to center the matrix character with respect to the mold-cavity.

3. In a machine for casting type, the combination of a mold comprising a stationary and an insertible part; a matrix-plate; a movable holder for the matrix-plate; and means carried by the insertible part of the mold and by which said matrix plate and holder may be shifted to center the matrix character with respect to the mold-cavity.

4. In the art of casting type a mold having a recess; a matrix-holder in said recess and a device for simultaneously locking the matrix-holder to the mold and centering the matrix character with respect to the mold-cavity.

5. In the art of casting type a mold, a holder carried by the mold and provided with means for receiving a matrix-plate so that the character on the latter will take a definite position with respect to the holder irrespective of the size of said character, and means for centering the matrix-holder and matrix with respect to the mold.

6. In the art of casting type a mold, a matrix-holder provided at one side with means for engaging a matrix-plate and at another side having means by which said holder may be positioned in the mold, and a device for engaging the said positioned means on the holder to center the matrix.

7. In the art of casting type a mold, a ma-

trix-holder provided at one side with means for engaging a matrix and at another side having a centering device, and a device carried by the mold and movable toward the 5 said centering device on the holder to center the matrix in the mold.

8. In the art of casting type a mold, a matrix-holder provided at one side with means for engaging a matrix and at another side 10 having a seat with an inclined wall, and a device carried by the mold and contacting with the said inclined wall of the holder to center the matrix.

9. In the art of casting type a mold, a matrix-holder provided with means for holding a matrix-plate with its character in a given 15 position with respect to the holder, and said holder also being provided with a centering-seat which has a given position with respect

to the character of any matrix in said holder, 20 and means coacting with said seat to center the matrix character with respect to the mold-cavity.

10. In the art of casting type a mold, a matrix-holder provided at one side with 25 means for holding a matrix and at another side having a centering-recess, and a screw carried by the mold and adapted to have its end enter the centering-recess of the holder to center the matrix in the mold. 30
